UNITED STATES PATENT OFFICE

163,085

SET OF SECTIONAL EDUCATIONAL TOY
BLOCKS

Katherine V. Bishop, San Gabriel, Calif.

Application July 8, 1950, Serial No. 11,026

Term of patent 7 years

(Cl. D34—15)

To all whom it may concern:

Be it known that I, Katherine V. Bishop, a citizen of the United States, residing in San Gabriel, in the county of Los Angeles and State of California, have invented a new, original, and ornamental Design for a Set of Sectional Educational Toy Blocks, of which the following is a specification, reference being had to the accompanying drawing, forming part thereof.

Fig. 1 is a plan view of a set of sectional educational toy blocks, showing my new design.

Fig. 2 is a perspective view of one of the blocks of the group shown in Fig. 1.

I claim:

The ornamental design for a set of sectional educational toy blocks, substantially as shown.

KATHERINE V. BISHOP.
